Inventor,
Arthur B. Utley,
By Mark A. Lehman,

Attorney

UNITED STATES PATENT OFFICE.

ARTHUR B. UTLEY, OF SPRINGFIELD, MISSOURI.

GRAPPLE.

1,356,841.

Specification of Letters Patent. Patented Oct. 26, 1920.

Application filed April 5, 1919. Serial No. 287,663.

To all whom it may concern:

Be it known that I, ARTHUR B. UTLEY, a citizen of the United States of America, and resident of Springfield, in the county 5 of Green and State of Missouri, have invented certain new and useful Improvements in Grapples, of which the following is a specification.

This invention relates to grapples and has 10 for its object the provision of novel means whereby fingers or clamping members may be operated to open and close, means being provided for mounting the said fingers so that they will operate when reciprocatory 15 motion is communicated to them, novel means being also provided for communicating said motion to them.

A further object of this invention is to produce a grapple having means whereby 20 the operating parts thereof may be kept free of fluid or fouling sediment.

The invention has reference particularly to a tool or device adapted to clean traps of water closets, the said device being also provided with an illuminating means which 25 can be lowered with the grapple so that the effect of the operation may be observed.

With the foregoing and other objects in view, the invention consists in the details of 30 construction and in the arrangement and combination of parts to be hereinafter more fully set forth and claimed.

In describing the invention in detail, reference will be had to the accompanying 35 drawings forming part of this specification, wherein like characters denote corresponding parts in the several views, and in which—

Figure 1 illustrates a sectional view of a 40 flush pipe and trap of a closet conventionally shown;

Fig. 2 illustrates a sectional view of the grapple, a fragment of the handle being shown in elevation;

Fig. 3 illustrates a view in elevation of 45 the lower portion of the grapple, and

Fig. 4 illustrates a view in elevation of the end of the casing with the grapples in section.

In these drawings 5 denotes a hollow handle in which a rod or operating handle 7 reciprocates. A ferrule 8 extends below the lower end of the handle and is internally threaded as at 9 to engage threads of a tube 10. The tube is externally threaded as at 11 to engage the threads of a coupling 12

and the said coupling 12 is connected to a housing 13 through the medium of a hollow boss 14, which is formed as a part of the housing. The outer end of the housing 13 60 has apertures such as 15 in which shanks 16 of the fingers or grapples 17 reciprocate, it being shown that the shanks 16 are at an angle to the grapples and as the said shanks move in the apertures 15, the outer ends of 65 the grapples are forced together or separated according to the direction of movement of the said shanks.

The inner ends of the shanks are shown 70 as provided with hooks 18 which extend through apertures 19 in the lower end of the operating rod 7, the said rod being slidable in the apertured boss 14.

The operating handle or rod 7 is under 75 the control or operation of a spring 26 which spring encircles the operating handle and bears against the end of the hollow boss and against a washer 21 which is on the said rod, the said washer being held against movement by a pin 22 extending through 80 the said rod. It will thus be seen that the action of the spring is to force the operating handle or rod outwardly or upwardly, and that when the said rod is manipulated or forced inwardly from the upper end of 85 the handle, the grapples or fingers will be worked to cause them to separate whereas the spring will return the rod 7 to normal position, causing the outer ends of the fingers to approach each other and form a 90 grapple or clamp which will hold the material lodged in the trap of a flushing system.

As a means for permitting the operator 95 to observe the progress of the work, a clip 23 is applied to the device near its lower end, and said clip is intended to carry an electric lamp 24, the conductor 25 of which may extend upwardly and be wound around the handle, so that the lamp will be moved into position when the operator is manipulating the grapple. 100

As shown in the drawing, the end of the casing comprises a plate 15^a having ears 15^b which extend into and lie in the recess 16^c within the casing and the plate is held in 105 place by fastenings 16^d such as screws.

The operating rod may be held at different positions of adjustment by a set screw 20.

I claim:

In a grapple, a hollow handle, an operating rod slidable therein, a tube detachably

connected to the handle, a housing having an aperture in its inner end communicating with the tube, means for detachably connecting the housing and tube, a plate bearing against the outer end of the housing, said plate having apertures therein, ears on the plate fitting within the housing, means for fastening the ears to the housing, said operating rod extending through the tube and be-

ing slidable in the housing, and grapples having hooks on their inner ends swingingly mounted on to the rod, said grapples having shanks angularly disposed with relation to the jaws whereby the shanks slide on the edges of the apertures of the plate and operate in said aperture.

ARTHUR B. UTLEY.
